(57) **CLAIM**

The ornamental design for a laser level, as shown and described.

DESCRIPTION

FIG. 1 is a perspective view of a laser level showing my new design;

FIG. 2 is a front elevation thereof;

FIG. 3 is a rear elevation thereof;

FIG. 4 is a side elevation as seen from the left side of FIG. 2;

FIG. 5 is a side elevation as seen from the right side of FIG. 2;

FIG. 6 is a top plan view thereof; and,

FIG. 7 is a bottom plan view thereof.

The broken lines shown in FIGS. 1, 2, 6 and 7 are for illustrative purposes only and do not form part of the claimed design.

1 Claim, 3 Drawing Sheets

FIG. 1**FIG. 2****FIG. 3**

FIG. 4**FIG. 5**

FIG. 6**FIG. 7**
